US00D631891S

(12) **United States Design Patent**
Vance et al.

(10) **Patent No.:** **US D631,891 S**
(45) **Date of Patent:** ** *Feb. 1, 2011

(54) **PORTION OF A DISPLAY SCREEN WITH A
USER INTERFACE**

5,867,226 A * 2/1999 Wehmeyer et al. 725/46
5,889,517 A * 3/1999 Ueda et al. 715/803

(75) Inventors: **Michael Steffen Vance**, Kenmore, WA (US); **Jasdeep Singh Chugh**, Renton, WA (US); **Feridoon Malekzadeh**, Seattle, WA (US); **Valerie Lynn Goulart**, Seattle, WA (US); **Jupiter Macleod Barton**, Seattle, WA (US); **Jared T. Benson**, Pleasant Hill, CA (US); **Christian Robertson**, Concord, CA (US); **Shilpa R. Shah**, Oakland, CA (US); **Gabriel J. White**, San Francisco, CA (US)

(73) Assignee: **T-Mobile USA, Inc.**, Bellevue, WA (US)

(**) Term: **14 Years**

(21) Appl. No.: **29/334,510**

(22) Filed: **Mar. 27, 2009**

(51) LOC (9) Cl. **32-00**

(52) U.S. Cl. **D14/487**

(58) Field of Classification Search D14/485-495;
715/700-867

See application file for complete search history.

(57) **CLAIM**

The ornamental design for a portion of a display screen with a user interface, as shown and described

DESCRIPTION

FIG. 1 is a front view of a portion of a display screen with a user interface showing the claimed design; and,

FIG. 2 is a front view of a portion of a display screen with a user interface showing the claimed design in accordance with a second embodiment.

The portion of the display screen and the portions of the user interface illustrated in broken lines form no part of the claimed design.

1 Claim, 1 Drawing Sheet
